UNITED STATES PATENT OFFICE.

AUGIE L. HANSEN, OF EVANSTON, ILLINOIS, ASSIGNOR TO JUSTRITE MANUFACTURING COMPANY, OF CHICAGO, ILLINOIS, A CORPORATION OF ILLINOIS.

TATTING-SHUTTLE.

1,276,524.

Specification of Letters Patent. Patented Aug. 20, 1918.

Application filed December 17, 1915. Serial No. 67,343.

To all whom it may concern:

Be it known that I, AUGIE L. HANSEN, a citizen of the United States, and a resident of Evanston, in the county of Cook and State 5 of Illinois, have invented certain new and useful Improvements in Tatting-Shuttles, of which the following is a specification.

My invention relates to tatting shuttles and contemplates improved construction and 10 arrangement.

Tatting shuttles are usually of elliptical form, the shuttle frame comprising two elliptical longitudinally bowed frames which are held together at their ends, and 15 a bobbin is disposed within the frame for receiving thread. In prior structures the bobbin is arranged between the frame usually with its axis perpendicular to the plate axes, and a special shape of bobbin is 20 therefore necessary, and usually no provision is made for mounting such bobbins on a machine for rapid winding.

The main object of my invention is to provide improved bobbin supporting mechanism within the shuttle frame for supporting a bobbin with its axis running lengthwise of the frame or parallel with the longitudinal axes of the plates. Such supports 25 may be sufficiently elongated to detachably received ordinary sewing machine shuttle bobbins, the advantage of this being that such bobbins will fit any sewing machine to 30 be easily and rapidly re-wound.

My improved construction is clearly 35 shown on the accompanying drawing in which

Figure 1 is a plan view with part of the top plate removed,

Fig. 2 is a side elevational view,

Fig. 3 is a sectional view on plane 3—3, 40 Fig. 2, and

Fig. 4 is a sectional view on plane 4—4, Fig. 2.

The shuttle frame is of the ordinary 45 shape and comprises similar top and bottom spherical plates 5 and 6 which are bowed longitudinally and secured together at their ends as by means of solder 7, the plates being preferably of sheet metal. Within

50 the shuttle frame is secured a U-shaped frame 8 of sheet spring metal having its limbs 9 and 10 extending transversely of the longitudinal axis of the spherical frame for

receiving between them a bobbin 11 with its axis parallel with the frame longitudinal 55 axis. The frame 8 may be secured in any manner. As shown, ears 12 and 13 extend laterally from the central part of the yoke of the frame 8 and are respectively secured to the inner faces of the plates 5 and 6 as 60 by soldering. Such central support of the frame 8 allows considerable spring play of the ends of the frame for the insertion and removal of bobbins. The bobbin I have shown is the same as that used in nearly 65 every sewing machine shuttle and such bobbins can therefore very readily be re-wound on any sewing machine. For receiving the pivot points 14 and 15 at the ends of the bobbin the limbs 9 and 10 have the 70 pivot sockets 16 and 17 deflected therein and to facilitate insertion of the bobbin ends in these sockets guide grooves 18 and 19 to these sockets are provided in the inner faces of the limbs. A wound bobbin can 75 thus be readily slipped between the limbs 9 and 10 and into pivotal engagement with the pivot sockets. To remove the bobbin it is necessary only to spread the limbs 9 and 10 slightly apart and the bobbin will drop 80 out.

I do not of course desire to be limited to the exact details of construction and arrangement shown as changes and modifications may no doubt be made which would 85 still come within the scope of the invention.

I claim as follows:

In a tatting shuttle, the combination with a shuttle frame comprising two elliptical plates secured together at their ends and spaced apart intermediate the ends, of a sheet metal bobbin holder comprising a U-shape body part having its limbs secured to the respective shuttle frame plates and 90 extending transversely thereof, arms extending from the yoke of said body part transversely between said plates and having opposed bearing sockets, and a bobbin 95 adapted to be inserted between said arms and having projections for engaging in said sockets.

In witness whereof I hereunto subscribe my name this 14th day of December, A. D. 1915.

AUGIE L. HANSEN.
